CLAIM

The ornamental design for an integrated dual container system as shown and described.

DESCRIPTION

FIG. 1 is a top, front perspective view of the claimed design for an integrated dual container system, according to a first embodiment;

FIG. 2 is a top view of the claimed design of FIG. 1;

FIG. 3 is a bottom view of the claimed design of FIG. 1;

FIG. 4 is a left side view of the claimed design of FIG. 1;

FIG. 5 is a right side view of the claimed design of FIG. 1;

FIG. 6 is a front view of the claimed design of FIG. 1;

FIG. 7 is a rear view of the claimed design of FIG. 1;

FIG. 8 is a top, front perspective view of the claimed design for an integrated dual container system, according to a second embodiment;

FIG. 9 is a top view of the claimed design of FIG. 8;
FIG. 10 is a bottom view of the claimed design of FIG. 8;
FIG. 11 is a left side view of the claimed design of FIG. 8;
FIG. 12 is a right side view of the claimed design of FIG. 8;
FIG. 13 is a front view of the claimed design of FIG. 8; and,
FIG. 14 is a rear view of the claimed design of FIG. 8.

The ornamental design that is claimed is shown in the drawings as solid lines and surfaces having surface shading. In the drawings, the evenly-spaced broken lines show portions of an integrated dual container system that form no part of the claim. The integrated dual container system is shown with a symbolic break in its width and length. The appearance of any portion of the article between these break lines and these break lines themselves form no part of the claimed design. Dash-dot-dash lines represent boundaries of the claimed design and form no part thereof. Any shading lines in the drawings show contour and not surface ornamentation.
